UNITED STATES PATENT OFFICE.

JAMES H. MILLER, OF PHILADELPHIA, PENNSYLVANIA, ASSIGNOR TO HIMSELF
AND CHARLES KRIPS, OF SAME PLACE.

DESIGN FOR A MEDALLION HEAD OF WASHINGTON.

Specification forming part of Design No. 5,150, dated August 1, 1871.

To all whom it may concern:

Be it known that I, JAMES H. MILLER, of Philadelphia, county of Philadelphia, State of Pennsylvania, have invented or produced a Design for a Medallion Head of Washington, of which the following is a specification:

The figure in the accompanying drawings represents my design, which consists of an alto relieve medallion head of Washington, facing to the left, the whole design being of a character too clearly shown in the drawings to need description.

I claim—

The design for a medallion head of Washington, substantially as described, and as represented in and by the accompanying drawings.

In testimony whereof I have signed my name to this specification in the presence of two subscribing witnesses.

JAMES H. MILLER.

Witnesses:

WM. A. STEEL,
HARRY SMITH.
